Atty.

UNITED STATES PATENT OFFICE.

HEINRICH BURCHARTZ, OF GELSENKIRCHEN, GERMANY, ASSIGNOR TO GELSEN-KIRCHENER BERGWERKS-A. G., OF GELSENKIRCHEN, GERMANY.

METAL-CASTING MACHINE.

Application filed December 10, 1924. Serial No. 755,105.

To all whom it may concern:

Be it known that I, HEINRICH BURCHARTZ, a citizen of Germany, residing at Gelsenkirchen, Germany, have invented certain new and useful Improvements in Metal-Casting Machines, of which the following is a specification.

My invention relates to metal casting machines and more particularly to means for casting hollow shapes such as for instance pipes by the centrifugal process. It is an object of my invention to provide a device in which the direction of the jet of molten metal is altered during the casting operation.

It has already been proposed to lead the jet in a lateral and tangential direction by means of nozzles which deflect the molten metal and which being rigidly connected with the casting spout render it impossible to alter the direction of the jet during the casting operation.

In the casting of pipes by the centrifugal process the first portion of the pipe to be cast is the sleeve. The metal required for the sleeve is preferably conducted into the mould in the axis of the spout so that the jet flows straight on. In order to cast the body of the pipe it is necessary to deflect the jet laterally so that it strikes the wall of the mould in the direction of its rotation. In order to obtain a larger cross-section at the opposite end of the pipe or to form a second sleeve thereon it is desirable to direct the jet to the side and to the rear.

This is effected according to this invention by a movable deflector at the end of the spout which can be adjusted to the required position by means of suitable links or levers which allow the jet to be deflected as desired.

In the drawings affixed to this specification and forming part thereof, several forms of a device embodying my invention are illustrated diagrammatically by way of example.

In the drawings,

Fig. 1 is an elevation of a spout having a deflector attached to it,

Figs. 2 and 3 are plan views of this spout, illustrating two different positions of the deflector,

Fig. 4 is a plan view of a spout provided with a curved deflector, and

Fig. 5 is a plan view of a spout having

a straight deflector adapted to deflect the jet laterally,

Figs. 6 and 7 are elevations of spouts provided with a curved and a straight deflector, respectively, designed to effect a deflection of the jet in vertical direction.

Referring first to Figs. 1 to 3, the deflector *b* is mounted for sliding motion on the spout *a* and is adapted to be displaced thereon by means of a rod *d*. The deflector is provided with a bend at its end and a slot *c* in its bottom. When the deflector is in the position shown in Figs. 1 and 2, the molten metal flows into the mould through the slot *c*, that is, in straight direction, as shown in Fig. 2. When the deflector *b* is moved in the position shown in Fig. 3, the bottom slot *c* is covered by the bottom of the spout so that the metal is deflected from its straight direction as shown. Any suitable means (not shown) may be used for controlling the position of the deflector.

If it is not desired to increase the cross-section of the pipe at the end opposite the sleeve or to cast a sleeve at that end also, it is not necessary to deflect the jet in lateral and rearward direction as shown in Fig. 3. In this case the deflector will be formed as indicated in Figs. 2 and 3 in dot and dash lines so that the jet is only deflected laterally, but not rearwardly.

In the modified forms disclosed in Figs. 4 to 7 the deflector *b* is pivoted to the spout *a*, *d* being the controlling rod.

As shown in Fig. 4 the deflector *e* is curved and fulcrumed to the spout at *g*. By means of the rod *d* the deflector can be bodily rotated above its fulcrum *g*, as shown in dot and dash lines.

In the form shown in Fig. 5 a straight-edged deflector *f* is arranged to be rotated by the rod *d* about a fulcrum *h*, the jet being deflected by horizontal displacement of the deflector.

The devices shown in Figs. 6 and 7 are similar to those shown in Figs. 4 and 5, the difference being that the jet is deflected by vertical displacement of the curved deflector *e'* about its fulcrum *i* on the spout *a* (Fig. 6) or of the straight deflector *f'* about its fulcrum *k* (Fig. 7).

I wish it to be understood that I do not desire to be limited to the exact details of construction shown and described, for ob-

vious modifications will occur to a person skilled in the art.

I claim:

1. Device for casting hollow bodies by the centrifugal process comprising a substantially horizontally arranged spout and a deflector movable on said spout and arranged for alternately allowing or barring the flow of metal from said spout in the direction of its axis.
2. Device for casting hollow bodies by the centrifugal process comprising a substantially horizontally arranged spout and a deflector movable on said spout and arranged for alternately allowing or barring the flow of metal from said spout in the direction of its axis.
3. Device for casting hollow bodies by the centrifugal process comprising a substantially horizontally arranged spout and a deflector axially movable on said spout and arranged for alternately allowing or barring the flow of metal from said spout in the direction of its axis.
4. Device for casting hollow bodies by the centrifugal process comprising a substantially horizontally arranged spout and a deflector with slotted bottom axially movable on said spout and arranged for alternately allowing or barring the flow of metal from said spout in the direction of its axis.
5. Device for casting hollow bodies by the centrifugal process comprising a substantially horizontally arranged spout and a horizontally curved deflector movable on said spout and arranged for alternately allowing or barring the flow of metal from said spout in the direction of its axis.
6. Device for casting hollow bodies by the centrifugal process comprising a substantially horizontally arranged spout and a horizontally curved deflector with slotted bottom axially movable on said spout and arranged for alternately allowing or barring the flow of metal from said spout in the direction of its axis.
